MOUNTING FOR HAND TELEPHONES

Hans Sengebush, Villa Park, Ill., assignor to Associated Electric Laboratories, Inc., Chicago, Ill., a corporation of Delaware

Application April 14, 1939, Serial No. 267,814

4 Claims. (Cl. 179—146)

The present invention relates to mountings for telephones and, more particularly, to desk mountings for hand telephones.

A mounting of this type conventionally comprises a supporting base, a pedestal carrying a calling dial, and a cradle provided with a switchhook and adapted to support a hand telephone or hand set of the well-known Monophone type; the usual substation apparatus, including an induction coil, a condenser, a signal bell and a switching mechanism, being housed in the supporting base and pedestal of the mounting.

It is an object of the present invention to provide a mounting of the type described which is of simple and rugged construction and which embodies an improved arrangement for facilitating movement from place to place of the mounting and the hand telephone supported thereby.

The object set forth above is attained in accordance with the present invention by providing a mounting of the character described comprising a base, a pedestal and a cradle including two spaced-apart and upwardly extending cradle members, the pedestal including front and rear upwardly and inwardly extending walls and upwardly extending side walls formed by the cradle members. The rear wall of the pedestal and the cradle members are so constructed and arranged that a substantially channel-shaped recess is provided in the rear of the pedestal, the cradle members being provided with aligned cradle seats therein adapted to support the hand telephone. An element having a handle portion is pivotally mounted on the cradle members, the element having a normal position wherein it is disposed substantially entirely in the recess provided in the rear of the pedestal and the handle portion thereof is disposed below the plane of the aligned cradle seats provided in the cradle members and an operated position wherein it is disposed substantially out of the recess provided in the rear of the pedestal and the handle portion thereof is disposed above the plane of the aligned cradle seats provided in the cradle members. The element is so constructed and arranged that the handle portion thereof is readily accessible in order to facilitate movement from place to place of the mounting and the hand telephone supported thereby when the element occupies its operated position; and an operating member is pivotally carried by the pedestal and operative to swing the element from its normal position to its operated position, the operating member being so constructed and arranged that it is readily

accessible adjacent the front wall of the pedestal.

The novel features believed to be characteristic of the invention are set forth with particularity in the appended claims. The invention, both as to its organization and method of operation, together with further objects and advantages thereof, will best be understood by reference to the following specification taken in connection with the accompanying drawing, in which Figure 1 is a perspective view of a mounting for a hand telephone which is constructed and arranged in accordance with the present invention; and Fig. 2 is a longitudinal sectional view of the mounting shown in Fig. 1 and a hand telephone supported thereby, illustrating the operated positions of certain elements of the mounting and the substation apparatus housed therein.

Referring now more particularly to the drawing, there is shown a desk mounting or support 10 for a hand telephone or hand set of the well-known Monophone type illustrated at 11, which mounting comprises a supporting base 12, a pedestal 13, and a cradle 14 including two spaced-apart and upwardly extending cradle members 15 and 16. The pedestal 13 is provided with front and rear upwardly and inwardly extending walls 17 and 18 converging slightly forwardly of the cradle 14, a top wall 19 extending between the front and rear walls 17 and 18, respectively, and upwardly extending side walls formed by the cradle members 15 and 16. The top and rear walls 19 and 18, respectively, of the pedestal 13 and the cradle members 15 and 16 are so constructed and arranged that a continuous substantially channel-shaped recess 20 is provided in the top and rear of the pedestal 13. Aligned cradle seats 21 and 22 are provided in the cradle members 15 and 16, respectively, the cradle seat 21 provided in the cradle member 15 being formed therein by spaced-apart and upwardly extending front and rear tines 23 and 24, respectively; and the cradle seat 22 provided in the cradle member 16 being formed therein by spaced-apart and upwardly extending front and rear tines 25 and 26, respectively. The cradle seats 21 and 22 provided in the cradle members 15 and 16 are provided with recesses therein into which two metal inserts 27 and 28, respectively, are securely positioned, the inserts 27 and 28 having openings 29 and 30, respectively, into which two switchhooks or plungers

31 and 32, respectively, are slidably mounted. The front wall 17 of the pedestal 13 is provided with an annular recess 17a therein within which a calling dial 31 is positioned and sup-

ported in place. The interiors of the supporting base 12 and the pedestal 13 are hollow in order to provide a continuous cavity 32 therein which accommodates the usual substation apparatus, 5 such as a signal bell 33, an induction coil 34, a condenser 35 and a switching mechanism 36, the switching mechanism 36 being operatively associated with the switchhooks or plungers 29 and 30 by a suitable connecting lever mechanism 37. 10 The opening into the cavity 32 formed in the supporting base 12 and the pedestal 13 is closed by a suitable base plate 38 fastened to the supporting base 12. Also, the mounting 10 is so constructed and arranged that the center of gravity 15 thereof is disposed in a substantially vertical plane extending through the aligned cradle seats 21 and 22 provided in the cradle members 15 and 16, respectively, in order to insure proper balance 20 of the mounting. 25 The handle of the hand telephone 11 is supported in the aligned cradle seats 21 and 22 provided in the cradle members 15 and 16, respectively, the weight of the hand telephone being adequate to retain the switchhooks or plungers 29 and 30 in their depressed positions against the bias of the switching mechanism 36, in order 30 to retain the switching mechanism 36 in its open circuit position in a well-known manner. When the handle of the hand telephone 11 is removed 35 from the supporting cradle seats 21 and 22 provided in the cradle members 15 and 16, respectively, the switchhooks or plungers 29 and 30 are projected outwardly under the bias of the switching mechanism 36, in order to cause the 40 switching mechanism 36 to be operated to its closed circuit position in a well-known manner.

In order to facilitate movement of the mounting 10 and the hand telephone 11 supported thereby from place to place, an arrangement is 45 provided which comprises an element 39 provided with a handle portion 40 and two outwardly extending pivot pins 41 and 42 arranged in aligned openings provided in the inserts 27 and 28, respectively. Accordingly, the element 39 extends 50 between the cradle members 15 and 16 and is pivotally mounted in the aligned openings provided in the inserts 27 and 28 carried by the cradle members 15 and 16, respectively. The element 39 has a normal position wherein it is 55 disposed substantially entirely in the recess 29 provided in the pedestal 13 and the handle portion 40 thereof is disposed below the plane of the aligned cradle seats 21 and 22 provided in the cradle members 15 and 16, respectively. Also, 60 the element 39 has an operated position wherein it is disposed substantially entirely out of the recess 29 provided in the pedestal 13 and the handle portion 40 thereof is disposed above the plane of the aligned cradle seats 21 and 22 provided in the cradle members 15 and 16, respectively. The element 39 is so constructed and 65 arranged that the handle portion 40 thereof is readily accessible in order to facilitate movement from place to place of the mounting 10 and the hand telephone 11 supported thereby when the element 39 occupies its operated position.

In order to actuate the element 39 from its 70 normal position to its operated position there is provided an operating member 43 having a substantially T-shape and including a stem 44, a head 45 and a button 46. The stem 44 of the operating member 43 is arranged in a longitudinally extending slot 47 provided in the rear wall 18 of the pedestal 13 and pivotally mounted therein 75 upon a pivot pin 48 extending through aligned

openings provided in the stem 44 of the operating member 43 and the top wall 19 of the pedestal 13. The head 45 of the operating member 43 is normally arranged in a laterally extending recess 49 provided in the rear wall 18 of the pedestal 13; while the button 46 of the operating member 43 is readily accessible adjacent the front and top walls 17 and 19, respectively, of the pedestal 13.

In order to actuate the element 39 from its normal position to its operated position the button 46 of the operating member 43 is depressed, thereby to cause the operating member 43 to be rotated in a counterclockwise direction, as viewed in Fig. 2, about the pivot pin 48. When the operating member 43 is rotated in the counterclockwise direction about the pivot pin 48, the head 45 thereof engages the element 39 and causes the element 39 to be swung in a counterclockwise direction, as viewed in Fig. 2, about the pivot 20 pins 41 and 42, whereupon the element 39 is moved from its normal position to its operated position. It is noted that when the element 39 occupies its operated position the handle portion 40 thereof is well above the plane of the 25 handle of the hand telephone 11, thereby to facilitate grasping of the handle portion 40 of the element 39 by a person wishing to move the mounting 10 and the hand telephone 11 supported thereby from one place to another. In 30 actuating the operating member 43 it is contemplated that the person wishing to move the mounting 10 and the hand telephone 11 supported thereby from one place to another will depress the button 46 of the operating member 35 43 with his thumb, whereupon the handle portion 40 of the element 39 will be swung to a convenient position above the plane of the handle of the hand telephone 11 in order to be grasped by the fingers of the person.

In view of the foregoing, it is apparent that a desk mounting for a hand telephone is provided which is of simple and rugged construction and which embodies an improved arrangement for facilitating movement from place to place of the 45 mounting and the hand telephone supported thereby.

While there has been described what is at present considered to be the preferred embodiment of the invention, it will be understood that 50 various modifications may be made therein, and it is contemplated in the appended claims to cover all such modifications as fall within the true spirit and scope of the invention.

What is claimed is:

1. A mounting for a hand telephone, comprising 55 a base, a pedestal, a cradle including two spaced-apart and upwardly extending cradle members, said cradle members being provided with aligned cradle seats therein adapted to support the hand telephone, said pedestal including front and rear upwardly and inwardly extending walls and upwardly extending side walls formed by said cradle members, the rear wall of said pedestal and said cradle members being so constructed and arranged that a substantially channel-shaped recess is provided in the rear of said pedestal, a movable element carried by said mounting and having a handle portion, said element having a normal position wherein it is disposed substantially entirely in the recess provided in the rear of said pedestal and the handle portion thereof is disposed below the plane of the aligned cradle seats provided in said cradle members and an operated position where- 65 70 75 80 85 90 95

in it is disposed substantially entirely out of the recess provided in the rear of said pedestal and the handle portion thereof is disposed above the plane of the aligned cradle seats provided in said 5 cradle members, the handle portion of said element being readily accessible in order to facilitate movement from place to place of said mounting and the hand telephone supported thereby when said element occupies its operated position 10 10, and an operating member carried by said mounting and operative to move said element from its normal position to its operated position.

2. A mounting for a hand telephone comprising a base, a pedestal, a cradle including two 15 spaced-apart cradle members, said cradle members being provided with aligned cradle seats therein adapted to support the hand telephone, an element having a handle portion and extending between said cradle members and pivotally 20 mounted thereon, said element having a normal position wherein the handle portion thereof occupies a position disposed below the plane of the aligned cradle seats provided in said cradle members and an operated position wherein the handle 25 portion thereof occupies a position disposed above the plane of the aligned cradle seats provided in said cradle members, the handle portion of said element being readily accessible in order to facilitate movement from place to place of said 30 mounting and the hand telephone supported thereby when said element occupies its operated position, and an operating member carried by said pedestal and operative to rotate said element from its normal position to its operated position.

3. A mounting for a hand telephone, comprising a base, a pedestal, a cradle including two 35 spaced-apart and upwardly extending cradle members, said cradle members being provided with aligned cradle seats therein adapted to support the hand telephone, said pedestal including front and rear upwardly and inwardly extending 40 walls and upwardly extending side walls formed by said cradle members, the rear wall of said pedestal and said cradle members being so constructed and arranged that a substantially channel-shaped recess is provided in the rear of said pedestal, the front wall of said pedestal having a 45 recess therein within which a calling dial is adapted to be supported, said base and said pedestal being adapted to house the usual substation apparatus, said mounting being so constructed 50 and arranged that the center of gravity thereof is disposed in a substantially vertical plane extending through the aligned cradle seats provided in said cradle members, an element having a handle portion and pivotally mounted on said 55 cradle members immediately below the aligned cradle seats provided therein, said element having a normal position wherein it is disposed substantially entirely in the recess provided in the rear of said pedestal and the handle portion thereof is disposed below the plane of the aligned cradle seats provided in said cradle members and an operated position wherein it is disposed substantially entirely out of the recess provided in the rear of said pedestal and the handle portion thereof is disposed above the plane of the aligned cradle seats provided in said cradle members, the handle portion of said element being readily accessible in order to facilitate movement from place to place of said mounting and the hand telephone supported thereby when said element occupies its operated position, and an operating member carried by said pedestal and operative to rotate said element from its normal position to its operated position.

handle portion thereof is disposed above the plane of the aligned cradle seats provided in said cradle members, the handle portion of said element being readily accessible in order to facilitate movement from place to place of said mounting 5 and the hand telephone supported thereby when said element occupies its operated position, and an operating member pivotally carried by said pedestal and operative to rotate said element from its normal position to its operated position, 10 said operating member being so constructed and arranged that it is readily accessible adjacent the front wall of said pedestal.

4. A mounting for a hand telephone, comprising a base, a pedestal, a cradle including two 15 spaced-apart and upwardly extending cradle members, said cradle members being provided with aligned cradle seats therein adapted to support the hand telephone, said pedestal including front and rear upwardly and inwardly extending 20 walls and upwardly extending side walls formed by said cradle members, the rear wall of said pedestal and said cradle members being so constructed and arranged that a substantially channel-shaped recess is provided in the rear of said pedestal, the front wall of said pedestal having a 25 recess therein within which a calling dial is adapted to be supported, said base and said pedestal being adapted to house the usual substation apparatus, said mounting being so constructed 30 and arranged that the center of gravity thereof is disposed in a substantially vertical plane extending through the aligned cradle seats provided in said cradle members, an element having a handle portion and pivotally mounted on said 35 cradle members immediately below the aligned cradle seats provided therein, said element having a normal position wherein it is disposed substantially entirely in the recess provided in the rear of said pedestal and the handle portion 40 thereof is disposed below the plane of the aligned cradle seats provided in said cradle members and an operated position wherein it is disposed substantially entirely out of the recess provided in the rear of said pedestal and the handle portion 45 thereof is disposed above the plane of the aligned cradle seats provided in said cradle members, the handle portion of said element being readily accessible in order to facilitate movement from place to place of said mounting and the hand 50 telephone supported thereby when said element occupies its operated position, and an operating member carried by said pedestal and operative to rotate said element from its normal position to its operated position.

HANS SENGEBUSCH.
